UNITED STATES PATENT OFFICE.

MATTHEW HOFFMAN, OF CHICAGO, ILLINOIS.

DESIGN FOR AN AUXILIARY STOVE-COVER.

SPECIFICATION forming part of Design No. 33,428, dated October 23, 1900.

Application filed September 29, 1900. Serial No. 31,582. Term of patent 31 years.

To all whom it may concern:

Be it known that I, MATTHEW HOFFMAN, a citizen of the United States, and a resident of Chicago, in the county of Cook and State 5 of Illinois, have invented a new and original Design for Auxiliary Stove-Covers, of which the following is a specification, reference being had to the accompanying drawings, forming a part thereof.

10 In the accompanying drawings, Figure 1 is a perspective view of an auxiliary stove-cover made according to my new design, said view being taken from the top of the device. Fig. 2 is a perspective view of the same, taken 15 from the bottom of the device.

The leading or material feature of my design consists in the flat top of substantially-rectangular outline having a circular aperture therein and having the depending flange 20 extending around said top and with the notches in the under edge of said flange.

The flat top 1 has the reinforcement 2, or thickened rim, surrounding the aperture 3. Said thickening is on the under side of the top or plate 1 and projects inward slightly, 25 so as to contract the aperture toward the under side of the plate 1, as shown in Fig. 1. The flange 4 extends around and downwardly from the top or plate 1, as shown in Fig. 2. The free or under edge of said flange is provided with notches 5, which are arranged on each side of the corners 6.

What I claim as new, and desire to secure by Letters Patent, is—

The design for an auxiliary stove-cover, 35 substantially as herein shown and described.

Signed by me at Chicago, Illinois, this 27th day of September, 1900.

MATTHEW HOFFMAN.
